ACID BOTTLE FOR WELL SURVEYING

Application filed August 4, 1930. Serial No. 472,931.

This invention relates to acid bottles for well surveying, and an object, in general, is to secure greater accuracy in surveying wells for variation from the vertical.

5 There is now used, in ascertaining the angle at which portions of a well-hole lie with respect to the vertical, a cylindrical glass container or bottle in which is placed a glass etching liquid, such as hydrofluoric acid. 10 When the bottle is lowered into a portion of a well-hole that lies at an angle with respect to the vertical portion of the hole, and is allowed to remain at rest for a certain length of time, the surface of the glass-etching liquid remains approximately horizontal and the said liquid etches the glass, thus making it possible when the bottle is removed from the well for the angle to be measured between the upper margin of the etching and one side 15 of the bottle.

The difficulty with using this old form of cylindrical bottle is that it does not give accurate results because of the fact that the upper side of the slanting bottle meets the surface of the etching liquid at a different angle than the lower side of said bottle. This results in the surface tension of the etching liquid being exerted with greater effect adjacent to the upper side of the tilted tube than 20 adjacent the lower side of said tube. In consequence of this, a less angle of variation from the vertical is indicated than actually exists in the well.

25 To overcome the objection noted above, we have devised a type of acid bottle in which the acid is held in a spherical or bulbous container or portion of a container. Tilting of the stem or straight portion of the bottle simply effects rotation of the spherical or bulbous portion about its axis and the etching liquid meets the opposite sides of the spherical wall at the same angles, and, accordingly, the surface tension acts with equal force at said 30 opposite sides and the surface of the etching liquid remains absolutely horizontal.

The accompanying drawing illustrates the invention:

Figure 1 is a longitudinal view of an acid 50 bottle for well surveying, constructed in ac-

cordance with the provisions of this invention.

Figure 2 is a view, partly in section, of the acid bottle shown in Fig. 1. The bottle is positioned aslant, as it would be in a slanting 55 portion of a crooked wellhole.

Figure 3 is a horizontal section on the line indicated by 3—3, Fig. 1.

Figure 4 is a fragmental view of an old cylindrical type of acid bottle. 60

Referring to Figures 1 to 3 of the drawing, there is provided a spherical hollow bulb 5 in which is placed a glass-etching liquid 6 of hydrofluoric acid or other liquid agent capable of etching glass, or other suitable 65 transparent material of which the bulb 5 is made.

In order that the angle of the etched portion of the bulb, relative to the axis of the well-hole, may be measured, the bulb 5 is provided 70 with a stem 7 which, in this instance, is also of glass and is cylindrical or tubular. In this instance, the stem and bulb are of integral construction, being blown or molded at the same time. 75

The upper end of the stem 7 is closed by a suitable stopper 8.

The invention operates as follows: The acid bottle will be lowered to any desired level in the well-hole that is to be surveyed, a record 80 being kept of the depth to which the acid bottle is lowered. The acid bottle will be left for a short interval of time in this position in the well so that the etching liquid will etch the inner surface of the bulb 5. If the stem 7 is 85 aslant to the vertical, as indicated in Fig. 2, the surface of the liquid will come to rest in a horizontal plane and, consequently, the upper margin of the etching liquid will be at an angle to the stem and this angle will absolutely 90 correspond to the angle of deviation of the well-hole from the vertical, since the effect of surface tension of the etching liquid on opposite sides of the bulb is exactly the same, because the angles of incidence are alike. 95

After the acid bottle has remained in the well a sufficient length of time to properly etch the bulb, it will be withdrawn from the well and the angle between the upper margin of the etching and the stem will be meas- 100

ured, thus giving the angle that the surveyed portion of the well-hole deviates from the vertical.

When the old type of acid bottle is employed in surveying a well, and comes to rest in a slanting position, as indicated in Fig. 4, the upper side of the bottle above the surface of the etching liquid makes an acute angle with the surface of said liquid, while the lower side of the bottle above said liquid makes an obtuse angle with the surface of the liquid. This difference in angles appears to have a decided effect in tilting the surface of the liquid out of the horizontal, it appearing that the effect of surface tension at the upper side of the bottle is greater than the effect of surface tension at the lower side of the bottle. The surface tension is, of course, the same at all circumferential points where the liquid contacts with the bottle. In the old type of bottle, if the vectors or lines, representing the force of the surface tension, be drawn for the upper and lower sides of the bottle, these vectors each resolves into its vertical and horizontal components, and it will be seen that the vertical component for the upper side is greater than the vertical component for the lower side.

When the bulb of this invention, however, is employed, the vertical components of the forces will, of course, be alike.

The old cylindrical type of acid bottles has a diameter of about $\frac{7}{8}$ of an inch and the bulb of our instrument may be made the same diameter so that the instrument may fit in the same size of "go-devil" as is employed for the old type.

We claim:

- 40 1. An acid bottle for well surveying comprising a stem, a spherical hollow transparent bulb of etchable material secured to one end of the stem, and a liquid in the bulb capable of etching said bulb.
- 45 2. A container provided with a spherical transparent portion of acid etchable material, and an acid in said spherical portion capable of etching said portion.
